UNITED STATES PATENT OFFICE.

HENRY H. YERK, OF DAVENPORT, IOWA, ASSIGNOR TO THE BETTENDORF COMPANY,
OF BETTENDORF, IOWA, A CORPORATION OF IOWA.

DROP-STAKE FOR LOGGING-CARS.

1,256,860.

Specification of Letters Patent. Patented Feb. 19, 1918.

Application filed October 28, 1915. Serial No. 58,398.

To all whom it may concern:

Be it known that I, HENRY H. YERK, a citizen of the United States of America, and resident of Davenport, Scott county, Iowa, have invented a certain new and useful Improvement in Drop-Stakes for Logging-Cars, of which the following is a specification.

My invention relates to cars especially adapted to the transporting of logs and the like, and is directed more particularly to the bunk stakes usually employed in cars of this nature, and to the stake operating means whereby the stakes are elevated and locked in operative position or released from opposite sides of the car, and has for its object to provide a stake which while permanently secured to the car and rigidly held in protruding position, to properly function as a load retaining means, yet can be easily and instantly released from its operative position and readily restored to and locked into operative position from the opposite side of the car, or restored to operative position from either side of the car.

To this end I have devised a stake of substantially arcuate or crescent form, pivotally connected at one end to the upper and inner side of a hollow bunk near each end thereof, and which by the straightening out of or flexing of toggle link connections can be protruded through the upper surface of the bunk into operative position, or withdrawn into the bunk into release position.

With these objects in view, my invention consists in certain novel features of construction and in certain parts and combinations hereinafter described and illustrated in the accompanying drawings, in which Figure 1, is a side elevation of a bunk taken on line A—B of Fig. 3, showing my improved device in operative position, Fig. 2 is a vertical longitudinal section taken on line C. D. of Fig. 3, showing one stake in operative position at one end of a bunk and a stake in release position at the other end, Fig. 3 is a top plan view of a bunk showing the center sills of a car frame broken off at each side of the bunk and showing my improved device in dotted and full lines. Fig. 4 is an end elevation of a bunk showing my device in operative position.

In these drawings in which similar characters of reference refer to similar parts throughout the several views, I have illustrated the preferred form of my invention, and have shown same as comprising a stake 1 of arcuate form, one end of which is pivotally connected to the upper part of a hollow bunk 2 on the inner side thereof as at 2^a in a manner to permit the other end of the stake to be protruded through a suitable opening 3 in the top of the bunk adjacent to the point of connection. The stake is preferably of substantially channel form made up of the web portion 4 and sides or flanges 5. Extending inwardly from the sides 5 near the free end of the stake are the bosses 6, between which one end of the link 7 is pivotally connected by the pin 8. Pivotally connected to the lug 9 in the bottom of the bunk by the pins 10 are the links 11—11. The upper end of these links are pivotally connected by the pin 12 to the link 7 at a point mediate its ends, and engaging opposite sides thereof. The lower end of link 7 is extended downwardly and inwardly out of the vertical plane of the upper portion, and is pivotally connected to the operating bar 13 by the pin 14, the end of the link 80 passing between the bifurcation in the end of the bar. The stakes 1 which are mounted in each end of the bunk are exact duplicates in form, method of attachment to bunk and mode of operation. They are both provided with the operating bars 13 which extend longitudinally through the bunk, at a sufficient angle to clear the stake at the other end of the bunk. The free end of these bars may be shouldered as at 15, so as to engage the lug 16 rising from the floor of the bunk. When the bar is thus engaged by the lug 16, the toggle links 7 and 11 are in a substantially vertical position with the bunk stake 1 protruded through the top of the bunk in operative position. As the points 8, 12 and 10 are practically in vertical alignment, the bar 13 can easily resist blows or shocks of most any magnitude to which the stakes may be subjected by a falling, swinging or rolling log.

By having attached bar 13 to the lower inwardly extending end of link 7, the bifurcated end of the bar when in its locked posi-

tion contacts the inner edge of links 11, acting as a stop preventing the toggle from flexing in the opposite direction which would permit the stake to partially drop 5 back into the bunk. This particular formation of link 7, and its attachment to the bar 13, also insures the positive lifting of the stake to operative position from its inoperative position as shown in Fig. 2 at the right hand 10 end of the bunk, as it will be observed, that with the stake lying normally in the bottom of the bunk, and with the operating bar 13 attached to the upturned end of link 7, the points A, B, and C cannot lie in the same 15 plane, but as the point C is considerably above the plane of points B and A, any longitudinal force applied to bar 13 is expended in lifting the stake by the straightening out of the toggle links 7 and 11.

20 By inserting a bar in the opening 17 formed in the side of the bunk near each end thereof, the end of bar 13 can be raised or pried upwardly sufficiently to permit the shoulder 15 to clear the lug 16, thereby releasing the bar and permitting the stake 1 to drop back into the bunk by the flexing of the toggle links 7 and 11. On the dropping of the stake within the bunk, the bar 13 moves longitudinally within the bunk, 25 presenting its free end to the opening 18 in the end of the bunk. The stake may be raised to operative position, either by grasping it directly and lifting it into position, or may be returned to and locked into oper- 30 ative position from the opposite side of the car by inserting a bar through the opening 18, and pushing against the end of bar 13, forcing the shoulder 15 back of lug 16. Thus it is seen that a stake can be released 35 or returned and locked into operative position from the opposite side of the car, or may be raised and locked into operative position 40 from the side of the car at which it is located, but as it can be released from the opposite side only, the danger of an operator releasing a load upon himself is avoided.

What I claim as new is—

1. In a device of the class described, the combination of a bunk extending across the car, and having openings at each end in its upper face, a drop stake adapted to extend through said opening above the bunk when in operative position, and to be withdrawn into the bunk when in its inoperative position, links arranged between said drop stake, and the floor of said bunk adapted to hold said stake in its operative position when said links are in a substantially vertical position,

and means extending across the car within the bunk releasably held from movement 60 whereby the said links are locked in said substantially vertical position.

2. In a device of the class described, the combination of a bunk mounted across the car, a stake pivoted to one end of said bunk 65 and extending upward therefrom when in operative position, and a bar secured to said stake above the said pivotal connections, and extending across the car, with its free end locked against longitudinal movement 70 whereby said stake is held in operative position.

3. In a device of the class described, the combination of a bunk extending across the car, of a stake of substantially arcuate form, 75 one end of which is pivotally connected to the inside of the bunk adjacent the upper surface thereof, with the other end free to be projected above the bunk to form the stake when in operative position, and to be 80 withdrawn into the bunk when in its inoperative position, a toggle link pivotally supported at one end to the floor of the bunk, and pivotally secured at the other end to the stake at a point mediate its ends, said 85 toggle adapted to be extended for elevating the stake to operative position, and to be flexed for withdrawing the stake within the bunk to inoperative position, and a bar pivotally secured to the extended end of one 90 of the links passing therefrom across the car within the bunk, an offset or shoulder formed in the free end of said bar, a transversely arranged lug in the floor of the bunk adapted to engage the said shouldered end 95 of said bar whereby the said stake is held in operative position, and means for raising said bar out of connection with said lug whereby said stake is released from its operative position.

4. The combination of a bunk extending across the car, a stake pivoted to the bunk arranged to project above the top of the bunk as its operating position, and to be withdrawn below the top of the bunk as its 105 non-operating position, a toggle comprising links pivotally connected together and to the stake and bunk and arranged when in substantial vertical alinement to support the stake in operating position, and means for 110 releasably locking the links in substantial vertical alinement.

Signed by me at Bettendorf, Iowa, this 26th day of October, 1915.

HENRY H. YERK.
